Atty.

UNITED STATES PATENT OFFICE.

KATHLEEN MONIMIA RAYMOND, OF AUCKLAND, NEW ZEALAND.

ELECTRIC IRON.

Application filed May 21, 1923. Serial No. 640,561.

To all whom it may concern:

Be it known that I, KATHLEEN MONIMIA RAYMOND, a citizen of the Dominion of New Zealand, residing at Indoar, Mt. Eden, city 5 of Auckland, Dominion of New Zealand, have invented certain new and useful Improvements in Electric Irons, of which the following is a specification.

This invention relates to electric irons and 10 has for its object the provision of means designed to prevent an iron from being left with the current on, when not being used.

According to the invention the iron is provided with a switch located in the handle, so that on the latter being gripped by 15 the user of the iron the electric circuit through the latter is closed, and the iron heated. The switch is closed against the action of a spring so that on the handle being released, the switch operates to open 20 and prevent the passage of current to the iron.

One of the wires in the flexible lead used with the iron is broken and has the ends adjacent the break, connected to separated 25 terminals on the handle. A member in the handle adapted to bridge the gap between the terminals is operated to complete the line, on the operation of a movable member, caused by the operator gripping the handle 30 of the iron during use. The movable member when the handle is gripped operates to effect the closing of the line, and the heating circuit through the iron, against the action of a spring, and on being released, 35 operates to bring about the opening of said line and circuit so as to prevent current from passing to the heating element within the iron.

A special feature of the aforesaid means 40 for opening and closing the circuit, is the construction which enables a quick and clean break in the circuit to be effected, and also which enables a quick and clean closing of the circuit to be brought about.

In order to enable this to be done the 45 member which bridges the gap between the separated terminals on the handles, is given sliding movement from the movable member operated by the hand or gripping the 50 handle, through a bell crank lever which engages in a slot in the bridging member. The latter has pivoted thereto short rods which pass one from each side of said bridging member, through slots in the frame of 55 the device. On these rods between the

bridging member and the frame compression springs are placed.

In order to complete the circuit through the iron, the bridging member is given movement towards the terminals, such action causing the springs on the short rods to be compressed and the inner ends of the latter to be moved towards said terminals until they are slightly beyond terminals at right angles to the bridging member. When 60 this occurs the springs on the short rods expand and suddenly shoot the bridging member into contact with both of the separated terminals and close the circuit through the iron. 70

On the handle of the iron being released the bridging member commences to move in a direction away from the terminals under the influence of a return spring, causing the springs on the short rods to be again 75 compressed and the latter to be moved slightly beyond positions at right angles to the bridging member, whereupon said springs again assert themselves and cause the opening of the circuit to be completed 80 with a quick action by the sudden withdrawal of the bridging member from engagement with the terminals.

In the accompanying drawing in conjunction with which the invention will be 85 further described,

Figure 1 is an elevation and

Figure 2 a plan view of an iron fitted with the improvement, the handle in each view being in section, and the circuit 90 through the iron being open,

Figure 3 is a sectional elevation and

Figure 4 a sectional plan of the handle of the iron, showing the bridging member, completing the gap between the terminals. 95

The handle 1 of the iron 2 is hollow and preferably of insulating material and is secured to the iron by screws 3 entering plugs 4 and 4^a from member 5. The plugs 4, 4^a are also of insulating material the latter being a fixture in one end of the handle 1 while the plug 4 is removable therefrom on taking out the screws 6. 100

In the handle 1 is a partition 7 of insulating material to which is attached a frame 105 8 also located in the handle 1 and removable therefrom with the partition 7.

The partition 7 carries terminals 13 to which are connected the two portions of a line 9 forming part of the circuit through 110

the iron, and broken to enable a gap in the circuit to be obtained as required. The two portions of the line are passed through the plug 4 which is bored to enable this to 5 be done.

The terminals 13 connect with separated contacts 10 on the opposite side of the partition 7, the gap between said contacts being closed when it is desired that current shall 10 pass through the iron, by means of a forked conductor 11 on the end of a rod 12 slidable in cross members 8^a of the frame 8.

The rod 12 is slotted as at 12^a near its outer end to receive one leg of a bell crank 15 lever 14 pivoted to the frame 8, the other leg of said lever 14 being connected by means of a link 15 with the outer end of a lever 16 of insulating material pivoted at its inner end to the frame 8 and projecting 20 from the handle 1.

A tension spring 17 connected at one end to a leg of the bell crank lever 14, and at the other end to an extension from the frame 8 acts to normally keep the forked conductor 25 11 away from the contacts 10 and the lever 16 projected from the handle 1.

Pivoted to the sliding rod 12, are a pair of short rods 18 which extend from the rod 12 through slots 19 in the side members 30 of the frame 8, said rods 18 having placed thereon between the rod 12 and the side members of the frame 8, compression springs 20.

Assuming the iron to be connected up 35 ready for use, the device operates as follows.

The action of the user of the iron in gripping the handle 1 forces the lever 16 upwards and causes the bell crank lever 14 to move the rod 12 in the direction of the contacts 10.

In their normal positions the short rods 18 have their pivoted or inner ends further from the contacts 10 than their outer ends, so that 45 movement of the rod 12 in the direction above mentioned causes the inner ends of the rod 18 to move towards the contacts 10 and the springs 20 to be compressed. On the rods 18 coming to positions slightly be- 50 yond at right angles with the rod 12, the springs 20 immediately expand and shoot the rod 12 forward, or cause the forked conductor 11 to smartly engage the contacts 10 and so close the circuit through the iron, 55 the slot 12^a in the rod 12, allowing the latter to overrun the bell crank lever 14.

So long as the lever 16 is kept up, the circuit is closed and current passes to the iron, but immediately said lever is released 60 the spring 17 pulls the bell crank lever 14 backwards and into contact with the rod 12 at the outer end of the slot 12^a causing the said rod 12 to commence to move in a direction away from the contacts 10. During the 65 first part of the latter movement the springs

20 are again compressed until such time as the rods 18 come to positions slightly beyond at right angles with the rod 12, whereupon said springs expand and complete the return movement of the rod 12 with a quick 70 action thereby ensuring a clean break being effected between the contacts 10 and conductor 11, the slot 12^a again allowing the rod 12 to over run the bell crank lever 14.

Stops 21, 22 on the rod 12 and frame 7 75 respectively, limit the return movement of said rod and the bell crank lever 14, while forward movement of the rod 12 is limited by the engagement of the conductor 11 with the contacts 10 and the engagement of the 80 rods 18 with a cross member of the frame 7.

A loop 23 on the handle 1 is provided for purposes of keeping the lever 16 up and the circuit through the iron closed when desired such as when heating the iron before commencing ironing, the loop 23 being however disengaged from the lever 16, immediately the iron is heated to the required temperature, in order that the current supply will be automatically cut in and out on the gripping 90 and releasing respectively of the handle 1.

What I do claim and desire to obtain by Letters Patent of the United States of America is:—

1. In an electric iron, a switch operating member fitted to the handle thereof; separated terminals in said handle; a conductor for bridging the gap between said terminals, operated by said member on the handle being gripped to close a circuit through the iron, and operating to open said circuit on the handle being released; and springs adapted to be compressed during the first portion of each movement of the conductor and then to expand and complete the movement of said conductor, wherein the conductor comprises a forked bridging member mounted on the end of a slotted sliding rod the latter being moved in one direction from a lever pivoted to the handle through a bell crank lever engaging in the slot of sliding rod, and connected by a link with said lever, said rod being moved in the reverse direction by a spring.

2. In an electric iron, a switch operating member fitted to the handle thereof; separated terminals in said handle; a conductor for bridging the gap between said terminals, operated by said member on the handle being gripped to close a circuit through the iron, and operating to open said circuit on the handle being released; and springs adapted to be compressed during the first portion of each movement of the conductor and then to expand and complete the movement of said conductor, wherein the forked bridging member is mounted on a rod slidable in a frame; said rod having pivotally connected thereto short rods which pass through opposite portions of said frame, and

- springs on said short rods, between the sliding rod and the frame.
3. In an electric iron, a hollow handle of insulating material mounted thereon; plugs 5 of insulating material closing the ends of said handle and a partition of insulating material in the latter; terminals on said partition and wires passing through a plug to said terminals; contacts on said 10 partition, connected with the terminals; a frame carried by said partition; a rod with a forked end and containing a slot slidable in said frame; a lever pivoted to said handle, and a bell crank lever pivoted to said frame, 15 so that one leg enters the slot in the sliding rod; a link between the bell crank lever and the lever pivoted to the frame 1; a tension spring between said bell crank lever and an extension from the frame; short rods pivoted to the sliding rod, passing through 20 opposite portions of the frame; springs on the short rods between the sliding rod and the frame; and stops on the frame and on the sliding rod for limiting movement of the latter and said sliding rod. 25

In testimony whereof I have signed my name to this specification.

KATHLEEN MONIMIA RAYMOND.
